UNITED STATES PATENT OFFICE.

ANDREW J. SELZ, OF NEW ROCHELLE, NEW YORK, ASSIGNOR TO PAPER BOTTLE AND CAN COMPANY, INC., OF WILMINGTON, DELAWARE, A CORPORATION OF DELAWARE.

PAPER BOTTLE.

1,342,769.

Specification of Letters Patent.

Patented June 8, 1920.

Application filed September 26, 1917. Serial No. 193,344.

To all whom it may concern:

Be it known that I, ANDREW J. SELZ, a citizen of the United States, and resident of New Rochelle, in the county of Westchester and State of New York, have invented a new and useful Improvement in Paper Bottles, of which the following is a specification.

The object of my invention is to produce a paper bottle which will be very strong and durable, which will be simple to manufacture and inexpensive, and which may be readily packed in a minimum space for shipment without danger of causing the collapse of the bottles.

A practical embodiment of my invention is represented in the accompanying drawings, in which—

Figure 1 represents the blank from which the bottle is formed,

Fig. 2 represents, in perspective, the bottle formed from the blank, certain portions being broken away to more clearly illustrate the parts behind the same, and

Fig. 3 is a similar view of a slightly modified form in which the folds along the upper portion of the bottle are exterior thereto instead of interior, as shown in Fig. 2.

The blank from which the bottle is formed is divided by the score lines 14, 15, 16 and 17, and slits 10, 11, and 12, 13, into a bottom 1, sides 2 and 3, projecting in opposite directions from the bottom, side members 4, 5, projecting laterally from the side 2, side members 6, 7, projecting laterally from the side 3, and flaps 8, 9, projecting from the bottom 1 at right angles to the sides 2 and 3.

In the completed bottle, the side members 5 and 7 are caused to overlap along one side of the bottle and the side members 4 and 6 are caused to overlap along the other side of the bottle.

The flaps 8 and 9 are turned upwardly to

form reinforcements along the lower portions of the overlapping side members 4, 6, and 5, 7, respectively.

The bottle is rectangular in cross section from bottom to top and the upper portion may be gradually reduced in size toward its top, by the provision of folds formed along the score lines 14 and 16, and the divergent score lines 18, 19; 20, 21; 22, 23; and 24, 25. These folds may be formed either along the interior of the bottle, as shown in Fig. 2, or along the exterior thereof, as shown in Fig. 3, said folds forming a very substantial reinforcement for the bottle.

In the completed bottle, it is to be understood that the overlapping side members and the folds and flaps are firmly glued or otherwise cemented and where the bottle is to be used for liquids the entire bottle may be treated with a suitable material, such as paraffin, to render the same moisture-proof.

It is also to be understood that any suitable closure may be provided for the top of the bottle.

Bottles produced from blanks as herein described will be very strong and durable and a number of them may be packed in a very small space for shipment without danger of their collapse.

What I claim is:—

A paper bottle formed of a single blank having a rectangular bottom, two oppositely arranged vertical sides and two oppositely arranged vertical bottom flaps projecting from the bottom and two pairs of oppositely arranged vertical overlapping side members, and folds extending partway the length of the bottle to gradually decrease the size of the upper portion of the bottle to its top.

In testimony that I claim the foregoing as my invention, I have signed my name, this 18th day of September, 1917.

ANDREW J. SELZ.
